Primary Examiner — Leah Simone Macchiarolo
Assistant Examiner — Margaret Leah Bryan

(57) **CLAIM**

The ornamental design for a nail file as shown and described.

DESCRIPTION

- 1.1: Perspective
- 1.2: Perspective
- 1.3: Front
- 1.4: Back
- 1.5: Left
- 1.6: Right
- 1.7: Top
- 1.8: Bottom
- 1.9: Enlarged

- 1.10: Enlarged
- 1.11: Enlarged
- 1.12: Enlarged
- 1.13: Enlarged top view
- 1.14: Enlarged bottom view

Fig. 1.13 is an enlarged top view of fig. 1.7; fig. 1.14 is an enlarged bottom view of fig. 1.8; the short-dash-long-dash broken lines depict the bounds of the enlarged views and form no part of the claimed design.

1 Claim, 10 Drawing Sheets
